UNITED STATES PATENT OFFICE.

PETER R. HOWE, OF FORTSVILLE, ASSIGNOR OF ONE-HALF TO CHARLES M. MOTT, OF GLENS FALLS, NEW YORK.

AUXILIARY RIFLE-BARREL AND EXTRACTOR THEREFOR.

SPECIFICATION forming part of Letters Patent No. 282,194, dated July 21, 1883.

Application filed January 22, 1883. (No model.)

To all whom it may concern:

Be it known that I, PETER R. HOWE, a citizen of the United States, residing at Fortsville, in the county of Saratoga and State of New York, have invented a new and useful Improvement on the Shelton Auxiliary Rifle-Barrel and an Extractor Thereto and Therefor, of which the following is a specification.

My invention relates to improvements in Shelton's auxiliary rifle-barrel to be used in breech-loading shotguns, and an extractor thereto and therefor, which extractor acts as a perfect lock to the barrel, preventing it from moving in a revolving manner, and operates as a perfect extractor of the empty shell or cartridge by the ordinary method of opening breech-loading guns. The rifle-barrel is made the full length of the shot-barrel, in which it is inserted, with a small flange-nut which screws on the end of the rifle-barrel after the same is inserted in the shot-barrel, the flange coming in contact with the muzzle of the shot-barrel, thus preventing the rifle-barrel from moving horizontally or being drawn by the extractor.

The Shelton auxiliary rifle-barrel is made as follows: The barrel is made six to ten inches shorter than the shot-barrel in which it is inserted, with a foul protector or tube attached thereto, making barrel and foul-protector the exact length of shot-barrel. There is a centering-collar placed around the muzzle of the rifle-barrel for the purpose of centering the rifle-barrel inside the shot-barrel. The breech of the barrel is made with a flange which extends around the barrel and rests on the groove or shoulder in the ordinary breech-loading shotgun-extractor, the purpose of which is to draw the barrel when opening the gun; so that it may be readily removed from the shot-barrel. The effect, however, of this continual drawing and replacing the rifle-barrel every time the gun is opened and shut is to wear upon the centering-collar, thus loosening the rifle-barrel inside the shot-barrel and throwing it from its central position therein and producing a revolving motion of the barrel on firing, there being no lock to prevent either the horizontal or revolving motion. The extractor used to eject the empty shells from this barrel is either an automatic or hand extractor.

My improvement is as follows:

In the drawings, Figure 1 is a longitudinal section of my improved rifle-barrel in position in a shotgun-barrel. Fig. 2 is a side elevation of rifle-barrel and attachments. Fig. 3 is a rear view of shot-barrels with rifle in place; Fig. 4, a side view of the extractors detached.

The letter *a* designates the barrel of a shotgun of usual construction; *b*, my improved rifle-barrel, having an enlargement, *d*, near the muzzle, which just fits the bore of the shot-barrel, and a screw-threaded portion, *e*, forward of this enlargement. The barrel *b* extends nearly or quite to the muzzle of the shot-barrel, and is secured at the muzzle by nut *c*, which screws on the thread *e* of the barrel, and has a collar at the front end of greater diameter than the bore of the shot-barrel.

At the rear of the rifle-barrel there is a flange, *f*, cut away in part to permit the operation of the extractor of the shotgun. The barrel also has a slot, *i*, for the passage of the extractor of the rifle-barrel.

The extractor *g* of the shot-barrels is of usual construction, except that it has a dovetail groove across its face, as shown in Fig. 4. In this groove the bar *h* is held to form an extractor for the rifle-barrel. The bar *h* can be turned so as to project at either side of the main extractor, so that an auxiliary barrel may be inserted into either one of the shotgun-barrels when properly constructed for the purpose.

The projection *d* on the rifle-barrel serves to center said barrel in the gun, and it is secured from endwise movement by means of nut *c* and flange *f*. The cut-away portion of flange *f*, as well as the groove *i*, serves to hold the rifle-barrel from rotation by engagement with the extractors, as shown and explained.

The only alteration necessary to apply my device to shotguns in common use is the cutting of the slot in the extractor, which does not change its usual mode of operation.

The whole device consists of but three parts —viz., the barrel, the retaining-nut, and the extractor. It is therefore simple and not liable to get out of order.

I claim—

1. The combination, with a shotgun-barrel, of an insertible rifle-barrel having retaining-

100

flange at its rear end, a flange which fits the bore of the shotgun, near its muzzle, both flanges being integral with the rifle-barrel, and a nut extending in front of the shot-barrel and engaging a screw-thread on the rifle-barrel, all substantially as stated.

2. The extractor of a double-barreled shotgun, having a dovetailed slot across its face, in combination with the extractor of an insertible rifle-barrel, constructed substantially as described, so that said extractor may be reversible and capable of operation on either side of said shot-cartridge extractor, as set forth.

3. The combination, with the shot-barrels and the extractor having a slot across its face, and the rifle-cartridge extractor, reversible, as described, of the insertible rifle-barrel, secured, as described, in the shot-barrel, and having a slot therein for the passage of the extractor, as set forth.

Dated September 25, 1882.

PETER R. HOWE.
